UNITED STATES PATENT OFFICE.

GEORG MERLING, OF ELBERFELD, AND HUGO KÖHLER, OF LEVERKUSEN, NEAR COLOGNE, GERMANY, ASSIGNEES TO FARBFENFABRIKEN VORM. FRIEDR. BAYER & CO., OF ELBERFELD, GERMANY, A CORPORATION OF GERMANY.

PROCESS OF PRODUCING BETA-METHYL-GAMMA-OXYBUTYLDIMETHYLAMIN.

1,074,967.

Specification of Letters Patent.

Patented Oct. 7, 1913.

No Drawing.

Application filed October 16, 1912. Serial No. 726,066.

To all whom it may concern:

Be it known that we, GEORG MERLING and HUGO KÖHLER, doctors of philosophy, chemists, citizens of the German Empire, residing, respectively, at Elberfeld and Leverkusen, near Cologne, Germany, have invented new and useful Improvements in Processes of Producing Beta - Methyl - Gamma - Oxybutyldimethylamin, of which the following is a specification.

In our applications Serial Nos. 724,635 and 730,017 we have described the production of the new base beta-acetyl-trimethylenetetramethylamin, which can be produced by the two-fold introduction of the

radical $-\text{CH}_2-\text{N}(\text{CH}_3)_2$ into acetone, *e. g.*, by treatment of acetone with a dimethylamino methane compound such as dimethylaminoxymethane (which can be produced by the action of dimethylamin on formaldehyde), either with or without a condensing agent. We have found that this new base the beta-acetyl-trimethylenetetramethylamin

20

can be easily decomposed by heating it with a dilute acid into dimethylamin and beta-acetylallyldimethylamin. This process proceeds according to the following equation:

30

The latter base can be easily reduced by means of the known reducing agents or electrolytically to the beta-methyl-gamma-oxybutyl-dimethylamin:

This product is identical with the oxy base obtainable by the reduction of the keto base:

prepared from methylene - methyl - ethylketone and dimethylamin.

In order to illustrate the new process more fully the following example is given, the parts being by weight:—1 part of acetyltrimethylenetetramethylamin (boiling point 96°-98° C. under a pressure of 16.5 mm.) is boiled during 1 hour with 4 to 6 parts of sulfuric acid (20 per cent.). Sodium amalgam is now gradually added to this solution which has to be cooled and stirred until a test portion no longer reduces potassium permanganate. During the process of reduction the solution has to be always kept acid by addition of sulfuric acid. The liquid is separated from the mercury and is then rendered alkaline with caustic soda lye or milk of lime and the oxy base is distilled with steam. The base is separated from the distillate as a colorless oil by the addition of caustic potash. It is dried with alkali and

finally distilled. Its boiling point 67°-69°

65

C. (17 mm.).

We claim:

1. Process for producing beta - methyl - gamma - oxybutyl - dimethylamin, which process consists in first converting beta-acetyltrimethylenetetramethylamin into beta-acetylallyldimethylamin by treating it with a dilute acid and then reducing the beta-acetyl - allyl - dimethylamin thus produced, substantially as described.

2. Process for producing beta - methyl - gamma - oxybutyl - dimethylamin, which process consists in first converting beta-acetyltrimethylenetetramethylamin into beta-acetylallyldimethylamin by treating it with dilute sulfuric acid and then reducing by means of sodium amalgam the beta-acetyl-allyl-dimethylamin thus produced, substantially as described.

3. The sub-process which comprises converting beta-acetyl-trimethylenetetramethylamin into beta-acetyl-allyl-dimethylamin by treating it with a dilute acid.

In testimony whereof we have hereunto set our hands in the presence of two subscribing witnesses.

GEORG MERLING. [L. S.]
HUGO KÖHLER. [L. S.]

Witnesses:

ALBERT NUERER,
HERMANN BERTRAMS.
